UNITED STATES PATENT OFFICE.

EDWARD H. ELLISON, OF JAMESTOWN, NEW YORK.

CONTROLLER FOR CASEMENT WINDOWS.

Application filed June 26, 1924. Serial No. 722,477.

To all whom it may concern:

Be it known that I, EDWARD H. ELLISON, a citizen of the United States, residing at Lakewood Road, in the city of Jamestown, 5 in the county of Chautauqua and State of New York, have invented certain new and useful Improvements in Controllers for Casement Windows, of which the following, taken in connection with the accompanying 10 drawings, is a specification.

This invention relates to an improvement in a controller for casement windows and more particularly to means for positively holding a window of that type in a pre-determined position and at the same time eliminating any vibration between the parts of the controller.

Controllers of this general type are old and well-known but it has been found that, 20 in every instance, the parts of the controller rattle and vibrate particularly when the window is opened and exposed to the wind.

The primary object of this invention is to avoid such an objection by the provision 25 of means for yieldingly engaging parts in close contact without interfering in any way with the operation of the controller.

Other objects will appear from a consideration of the following specification taken 30 in connection with the drawings which form a part thereof, and in which

Fig. 1 is a front elevation of a swinging window assembly provided with a controller embodying one form of this invention;

Fig. 2 is a plan view of the window and controller, the upper part of the casing being removed and the window being shown closed;

Fig. 3 is a view similar to Fig. 2 the window being shown partly open;

Fig. 4 is a bottom plan view of the gear mechanism by which the window controller is actuated;

Fig. 5 is a view on an enlarged scale of 45 a portion of the gear mechanism;

Fig. 6 is a fragmentary sectional plan view taken along the line 6—6 of Fig. 5;

Fig. 7 is a fragmentary sectional plan view taken along the line 7—7 of Fig. 5; 50 and

Fig. 8 is an enlarged detailed view showing another feature of this invention.

Referring to the drawings the reference 55 numeral 10 is employed to designate a window casing provided with a casement win-

dow 11 secured to the casing at one side by the hinges 12. Suitably mounted in the casing 10 on the opposite side from the window 11 is a screen 13 which may be secured in position in any desired manner. A window 60 of the side opening type is shown for purpose of illustration but it will be understood that the invention may be installed equally well upon any other type of hinged window and that applicant is in no way 65 limited to the type particularly shown.

The window controller mechanism designated broadly by the numeral 14 comprises a gear mechanism 15, enclosed in a casing 16 and adapted to actuate an arm 17 the 70 outer end of which slidably engages a bar 18. The bar 17 which is hollow, is rigidly secured to the frame of the window 11 by standards 19, and is provided on its underside with a slot 20 which extends from one 75 standard to the other. The gear mechanism 15 comprises a toothed segment gear 21 which engages a worm 22. One end of the worm 22 is seated in and extends through a sleeve 23 threadedly secured in the casing 80 16 and is provided with a rectangular socket which receives one end of the operating handle 24. The handle 24 is passed through a hole (not shown) in the frame of the screen and thus the window is opened or closed 85 without removing or opening the screen. The other end of the worm rests in a slot or recess 25 which as shown particularly in Fig. 7 holds the worm against the movement parallel to the axis of the gear 21 but 90 permits movement of that end of the worm toward and from the gear.

It is obviously very difficult to provide a worm and gear so formed that under all conditions the parts will mesh perfectly and 95 obviously if there be any high spots on the gear it is necessary under normal conditions to mount the worm so that when the high spots are in engagement there will be no binding between the worm and the gear. 100 Hence if this practice is followed when the worm and gear are in mesh at other than the high spots of the gear there will be a certain amount of play between the parts. In order to obviate this and to insure close 105 engagement at all times a plate 26 is provided from the rear of which projects a pin 27 which is surrounded by a coil spring 28 bearing against the wall of the casing and against the plate 26 thus yieldingly holding 110

the worm at all times in close engagement with the gear 21, the sliding mounting of one end of the worm previously described permitting the latter under the urge of the 5 spring 28 and the plate 26 to move toward or from the gear.

The arm 17 is rigidly carried on the shaft 29 of the gear so that when the gear is rotated by the worm 22 upon the turning of the 10 handle 25 the arm 17 will turn with the shaft 29. At the outer end of the arm 17 is formed a boss 30 through which extends a screw 31 threaded into an opening in a block 32 which is slidably mounted in the bar 18 the screw 15 31 extending through the slot 30 in the under side of the bar in order to hold the block in position and to prevent any play between the block and the bar a spring 33 is provided which yieldingly holds the block at all times 20 in contact with one side of the bar 18.

The only parts of the controller which are not rigidly held in engagement are the block 32 which is carried by the arm 17 and the bar 18 and the gear 21 and worm 22. 25 Any play or vibration that might be set up in this construction will, therefore, be at one of these two points and in order to avoid this the spring 33 and plate 26 and spring 28 have been provided.

30 While one embodiment of this invention has been shown and described, I am not to be limited thereto since it is obvious that others may be made without departing from the spirit and scope of the invention as set 35 forth in the following claims.

Having thus set forth my invention which

I claim as new and for which I desire protection by Letters Patent is:

1. A controller for a casement window consisting of a slotted bar mounted upon the window, an arm in sliding engagement with said bar, a gear mechanism for actuating said arm, said mechanism comprising a segment gear and a worm meshing with said gear and means for rotating said worm, and 45 means for yieldingly holding said arm in engagement with said bar and said worm in engagement with said gear.

2. A controller for a casement window consisting of a slotted bar mounted upon the 50 window, an arm in sliding engagement with said bar, a gear mechanism for actuating said arm, said mechanism comprising a segment gear and a worm meshing with said gear and means for rotating said worm, a 55 spring for yieldingly holding said arm in engagement with said bar and a spring pressed plate bearing upon said worm and holding it in yielding engagement with said gear.

3. A controller for a casement window 60 consisting of a slotted bar mounted upon the window, an arm in sliding engagement with said bar, a gear mechanism for actuating said arm, said mechanism comprising a segment gear and a worm meshing with said 65 gear and means for rotating said worm, and a spring pressed plate bearing upon said worm and holding it in yielding engagement with said gear.

In testimony whereof I have affixed my 70 signature.

EDWARD H. ELLISON.
